FISH HOOK REMOVER

Gary C. Rodgers, 8222 Gault Lane, Apt. 705,
San Antonio, Tex. 78209

Filed Sept. 11, 1973, Ser. No. 396,218

Term of patent 14 years

Int. Cl. D22—05

U.S. Cl. D22—31

FIG. 1 is a longitudinal side view of the fish hook remover;

FIG. 2 is a cross section taken along line 2—2 of FIG. 1;

FIG. 3 is a perspective view of the fish hook remover; and

FIG. 4 is a bottom end view of the fish hook remover.

I claim:

The ornamental design for a fish hook remover, as shown.
